UNITED STATES PATENT OFFICE

NELSON E. FUNK, OF NEW YORK, N. Y., ASSIGNOR TO FRANK D. BERRY, OF NEW YORK COUNTY, NEW YORK

PROCESS OF MAKING PAPER ARTICLES

Original application filed October 3, 1927, Serial No. 223,659. Divided and this application filed May 21, 1928. Serial No. 279,334.

This invention relates to improvements in processes for the manufacture of paper articles and is a divisional application of applicant's copending application Ser. No. 223,659 filed October 3, 1927.

It is a particular object of this invention to provide a process for making paper articles of a plurality of plies of expandible paper.

This invention is particularly applicable to egg flats, especially those with cross corrugations, and those flats for use in the packing of other fragile articles.

In the past it has been proposed to make such flats of cardboard or heavy paper by stamping the supporting projections out of said material. Since neither cardboard nor paper will stretch the obvious result is that the material will break at the points of deformation, and will be useless for the purpose intended. Furthermore, the fibres of paper having set once in a definite position in the original manufacture of the paper always tend to return to normal position after deformation, thereby causing the projections on the flat to assume irregular positions. For these reasons none of the early devices were, to applicant's knowledge, commercially successful or commonly used. A later development of the art to overcome some of the above mentioned deficiencies, was to manufacture said flats from loose fibres such as pulp, by pressing them in sheet form into the desired shape, while damp, and then drying. But though this development overcame some of the objections to earlier devices, it was open to objections of a different nature although fully as serious.

The main objections to this type of flat are that in the first place there is not sufficient cohesion between the fibres to withstand any substantial pressure, and secondly, and of greater weight, that, pulp, having a very strong affinity for water, they rapidly absorb moisture from the cool damp air to which they are usually subjected, becoming limp and useless for the purpose intended.

To overcome these objections as well as objections to earlier devices, applicant has formed a flat of expandible paper, an example of which is the well-known crepe paper.

This type of paper contains numerous small crinkles which, if any stress is put upon the paper, straighten out, giving greater surface to the paper. It must be understood that the paper itself does not stretch but that the increase in size is due to the smoothing out of said crinkles.

Likewise in forming paper articles such as cups, plates etc. from a plurality of plies or ordinary paper where an embossing operation is necessary to form the object desired, there is a great deal of difficulty in obtaining a proper edge on the object for the reason that during the embossing operation the several plies slip on each other whereby the edges are staggered. According to applicant's invention an edge of uniform thickness is obtained due to the fact that the expandibility of the paper provides for the slippage taking place during the embossing operation.

In practising this invention a plurality of layers of such paper are superimposed and united by a water-proof glue, for which purpose a solution of sodium silicate is preferred for the reason that it is very stable, sets very hard and is flexible when set. After the layers of paper are so bound and before the glue is set they are subjected to an embossing operation. Due to the fact that the glue is still damp, the various layers are movable relative to each other whereby allowance is made for necessary slippage between layers when making curved surfaces. In addition to this, the strains to which the paper is subjected during the embossing operation are taken care of by the expandibility of the paper, as pointed out above, and the finished article presents a substantially smooth appearance. The thickness of paper used is governed by the weight of article desired. All the layers may be of the same thickness or the middle layers may be of greater thickness than the outer layers, but whatever be the thickness, the paper must be creped or made expandible by some other method, or the product will be unsatisfactory.

This process is illustrated in the accompanying drawings in which:—

Fig. 1 is a side view of an arrangement of mechanisms for carrying out the process.

Fig. 2 represents a plan view of a flat.

Fig. 3 is a vertical section of a packing unit in use slightly enlarged to show the plies of the flat.

- 5 Referring to the drawings in detail, A, B and C are rollers carrying a supply of paper from which the various strips are let off and entrained over idlers not numbered. The strip from roller A passes through a 10 pair of creping rollers 3 and 4, by which is meant rollers that are so constructed that they break and gather the fibres both longitudinally and transversely of the web, thus supplying a surplus of paper so that when 15 the raised portions are embossed the paper is not fractured. In like manner, the paper from roll C passes between creping rollers 5 and 6. The paper from roll B being the middle layer, after passing through creping 20 rollers 1 and 2 passes around roller 25 in a vat 26 filled with sodium silicate solution of desired consistency, and from there passes through rollers 24 which remove the excess of adhesive which drops back into the tank. 25 Rollers 22 and 23 are pressing rollers through which the strips pass simultaneously. 7 and 8 are feed rollers which feed the combined strips from rollers 22 and 23 to platen 11. 13 is a knife reciprocated by eccentric 17 30 on the shaft of disc 19 which is in contact with the driving disc 20. Mounted adjacent the knife 13 is a stop 12 which binds the strips against the platen 11 on the downward motion of the knife 13 thereby stopping their 35 movement until the knife has cut off the desired length. Rollers 9 and 10 are feed rollers which move the paper onto plate 15 which is the female member of a die, and which is heated by steam or other common means. 40 The male member of the die 14 is reciprocated by an eccentric 16 on the shaft of the disc 18 which is connected to the driving disc 20. 21 is a conveyor for removing the finished article.
- 45 As shown in Figs. 2 and 3, the finished flat is made up of three plies of material, although it is not limited to this number and is corrugated transversely and longitudinally, the corrugations 29 being pressed 50 downwardly and intersecting to form sections 30 of which there are usually thirty-six to a flat. Centrally located in each section is a convex portion 31 pressed upwardly from the flat. In the center of each convex portion 55 is a concavity 32 formed by pressing the convex portion in the opposite direction.
- A further advantage of these flats is that they are very light thereby reducing shipping expenses both when in use and when shipped 60 empty in nested relation.
- Having thus fully described the invention as practiced, to which description, however, the invention is not limited, it only being the preferred form and capable of various modifications and alterations within the scope of

the invention, what is claimed as new is:—

1. The process of making embossed paper articles in a continuous operation consisting in entraining a plurality of plies of paper over rollers, creping each ply, applying a 70 water-proof glue to both sides of the inner ply, pressing the plies together without drying the glue, cutting the plies into proper length, embossing each length while the glue is still wet, and simultaneously drying the 75 glue.

2. The process of making embossed paper articles in a continuous operation consisting in entraining a plurality of plies of expandible paper over rollers, applying a water-proof 80 glue to both sides of the inner ply, pressing the plies together without drying the glue, cutting the plies into proper length, embossing each length while the glue is still wet, and simultaneously drying the glue. 85

3. The process of making egg flats in a continuous operation consisting in entraining a plurality of plies of expandible paper over rollers, applying a water-proof glue to both sides of the inner ply, pressing the plies 90 together without drying the glue, cutting the plies into proper length, embossing each length while the glue is still wet, whereby slippage of the several plies with respect to each other is allowed, and drying the glue 95 simultaneously whereby the embossed length is stiffened.

4. In the process of forming egg flats of several plies of expandible paper glued together the steps of embossing the flats while the glue is still wet whereby relative slippage is allowed between the several plies and simultaneously applying heat whereby the glue is dried and the embossed flat stiffened. 100

5. The process of making egg flats comprising the steps of binding together with wet glue a plurality of plies of crepe paper and embossing raised egg supporting portions on said plies while the glue is still wet whereby relative slippage is provided between the several plies and the crinkles in the plies are smoothed out, at the same time applying heat to dry the glue and stiffen the combined plies in embossed condition. 110

In testimony whereof I have hereunto set 115 my hand.
